UNITED STATES PATENT OFFICE.

WILLIAM H. FAUBER, OF CHICAGO, ILLINOIS.

DESIGN FOR A CRANK-ARM AND SPROCKET-WHEEL FLANGE.

SPECIFICATION forming part of Design No. 28,214, dated January 25, 1898.

Application filed September 18, 1897. Serial No. 652,199. Term of patent 7 years.

To all whom it may concern:

Be it known that I, WILLIAM H. FAUBER, a citizen of the United States, residing in the city of Chicago, county of Cook, and State of Illinois, have invented a new and useful Design for the Crank-Arm and Sprocket-Wheel Flange for Bicycle Crank-Axes, of which the following is a specification, reference being had to the following drawings, forming a part thereof.

In said drawings, Figure 1 is a view of a crank-arm and sprocket-wheel flange made in accordance with my novel design. Fig. 2 is a side elevation thereof. Fig. 3 shows a cross-section of the arm, taken on line 3 3 of Fig. 1. Fig. 4 is a cross-section taken on line 4 4 of Fig. 2.

My novel design relates more particularly to a crank-arm and sprocket-wheel flange made in one piece or integral with each other. Said crank-arm is made with four flat oblique faces, giving to the arm a lozenge or diamond shape in cross-section. The sprocket-wheel flange is of circular form and is provided with a flat outer face and a cylindric peripheral surface, at the inner margin of which is located a marginal radial flange which forms, with the peripheral surface of the main flange, a marginal annular recess or rabbet. The crank-arm is located with respect to the flange in a plane outside of the same and with the outer face of the flange approximately in the same plane with the inner surface of the arm, said arm being joined to the outer face of the flange in such manner that the inner end of said arm forms in effect a radial rib or projection on the flange extending from its central part outwardly until it is merged into the arm proper. The said arm is of diamond or lozenge shape, as described, in its part which extends outwardly beyond the flange only, and the oblique faces of the arm are so arranged that two of its opposite angles are located at the sides of the arm and in its plane of rotation, while the two other angles are located at the inner and outer faces of the arm midway of the sides thereof and in a plane which passes through the central axis of the sprocket-wheel flange. Said arm is, moreover, of greater width between its lateral angles than between its inner and outer angles, so that its width is greater as viewed from the

front than as viewed from the side. The two oblique faces at the inner side of the arm terminate at the cylindric outer surface of the flange and are merged into the same by concave surfaces, as clearly seen in Fig. 2. The two oblique surfaces at the outer face of the arm, however, extend along the inner portion of the arm, which extends over the flange, and terminate near the center of said flange. The side faces of said inner part of the arm are flat, parallel to each other, and perpendicular to the face of the flange, and said side faces are joined to the flat outer face of the flange by short concave surfaces or fillets. The inner part of the arm terminates at its inner end in a convex or spherically-curved surface which merges into the flat faces at the sides of the arm and which as the arm is seen in side view is defined by a circular quadrant which terminates in the line defining the outer angle or corner of the arm, as clearly seen in Fig. 2. Such convex or rounded surface is connected with the flat outer face of the flange by a short concave fillet in the same manner as are the flat side faces of the inner end of the arm, such concave surface or fillet in fact extending entirely around the side and end surfaces at the inner end of the arm, as clearly seen in Fig. 1. The two outer oblique surfaces of the arm which meet at the outer central angle thereof are extended in oblique planes until they intersect the spherical or rounded surface above referred to, their intersection with said surface forming angles which are defined by approximately-semicircular lines which extend from said outer or central angle of the arm to the side angles of the latter, where they merge into the lines formed by the angles between the flat side faces and the oblique faces of the inner end portion of the arm. The said arm is provided on its outer end with a circular enlargement or head within which is formed a circular opening, the central axis of which is parallel with the axis of the shaft. Said enlargement or head is provided on its inner and outer faces with parallel flat surfaces and is rounded on its peripheral surface. The arm itself is of greatest width at its point of connection with the flange and tapers gradually outward to the head referred to.

The side faces of the arm immediately ad-

jacent to the hub at the outer end thereof are convexly rounded, and the oblique surfaces at both the inner and outer faces of the arm terminate in convex outwardly-curved surfaces which intersect both the lateral convexly-rounded surfaces of the arm and the flat inner and outer faces of the boss to form angles which are defined by curved lines, the angles at the side faces being on oppositely-10 curved lines which intersect at the central angular line of the arm and diverge until they merge into the circular line which defines the end of the boss, as seen in Fig. 1, while the angles at the sides of the boss diverge from the lateral angle of the arm to the front and rear faces of the boss and thereby give to the convexly-rounded side faces of the arm approximately the form of a triangle, as seen in Fig. 2.

The essential or characteristic feature of my design is embraced in the arm made of 20 lozenge shape exterior to the flange, in connection with a flange having a flat outer surface, said arm having in its part which overlaps the flange parallel side faces and a spherical rounded end and having its oblique faces 25 at its outer side extending to the said spherical rounded surface and intersecting the same in a manner to form two semicircular angles.

I claim as my invention—

The design for the crank-arm and sprocket- 30 wheel flange of a velocipede, substantially as shown and described.

WILLIAM H. FAUBER.
